UNITED STATES PATENT OFFICE.

HENRY GEHRING, OF CINCINNATI, OHIO.

SLICING KNIFE.

Application filed April 18, 1922. Serial No. 555,207.

To all whom it may concern:

Be it known that I, HENRY GEHRING, a citizen of the United States of America, and a resident of Cincinnati, in the county 5 of Hamilton and State of Ohio, have invented a new and useful Improvement in a Slicing Knife, of which the following is a specification.

An object of my invention is to provide 10 a slicing knife which may be readily used by any person regardless of whether or not he be left handed or right handed.

Another object of my invention is to provide a device of this kind in which the parts 15 may be adjusted in relation to one another whereby to vary the thickness of the slices.

Another object of my invention is to provide a simple and efficient device for the purposes as stated.

20 Another object of my invention is to provide a device, the parts of which may be readily assembled and disassociated whereby to effect thorough and ready cleansing and sterilization thereof.

25 These and other objects are obtained by means described herein and disclosed in the accompanying drawing, in which:

Fig. 1 is a plan view of a device embodying my invention.

30 Fig. 2 is an enlarged sectional view on line 2—2 of Fig. 1.

Fig. 3 is an enlarged sectional view on line 3—3 of Fig. 1.

35 My invention consists of a blade holder 4 having a shank 5 whereby same may be mounted on a suitable handle 6. The blade holder comprises spaced parallel arms 7 and 8 extending lengthwise of itself, whereby a substantially rectangular slot 9 is formed 40 lengthwise of such holder. The forward end of the holder is preferably developed into a point 10 wherewith to remove the eyes from potatoes, etc.

45 The holder has formed in it the bores 11 and 12, said bores extending thru the holder in the same direction as does the slot 9, the axes of the bores 11 and 12 being in alignment with the longitudinal center line of the slot 9. The bores 11 and 12 are preferably 50 circular, although they need not be so. A blade 13 has mounted at its opposite ends, pins 14 and 15, the pins being spaced from one another at a distance equal to the distance at which the bores 11 and 12 are 55 spaced from one another. The pins are of a diameter such that they may be moved thru

the bores 11 and 12. The free ends of the pins have a series of grooves 16 formed in them whereby there are formed a series of spaced annular flanges 17 on the free ends 60 of the pins. Clips 18 and 19 are mounted on the holder, and are similar in shape, form and function. These clips comprise a body portion 20 and turned over edges 21 and 22 whereby the clips may be mounted on the 65 holder and be slid or reciprocated thereupon. The clips have slots 23, the slots being formed in the body portion and being of a width intermediate the diameters of the reduced portions 24 formed on the pins 70 and the flanges 17 formed on the pins. The opposite longitudinal edges of the blade are developed into cutting edges as shown at 25 in Fig. 3. A rib 26 is formed on and extends longitudinally of the blade, and lies 75 substantially midway of the cutting edges. When the blade is mounted in an operative position upon the holder, the ridge extends upwardly into the slot 9 formed in the holder, wherefore, when an article is being 80 sliced, the slices are projected thru the slot 9 thereby precluding clogging of the cutting edge.

The clips are used to secure the pins in various adjusted positions, the pins in turn 85 spacing the blade at various distances from the holder, whereby the thickness of the slices may be varied. When the clips are disassociated from the pins, the entire cutting blade may be disassociated from the 90 holder thereby permitting thorough cleaning of the holder and the blade. The clips in turn can be removed from the holder by being slid over the pointed end of the holder, thereby permitting cleaning of the 95 clips. It should be observed that when the clips and the blade have been removed from the holder there is left on the holder no inaccessible places where any foreign matter may lodge.

100 What I claim is:

1. In a device of the class described the combination of a holder having a pair of bores, a blade having a cutting edge, pins mounted on the blade, the pins being 105 adapted to be reciprocated in the bores whereby to space the cutting edge of the blade at various distances from the holder and having grooves formed in them, and clips slidably mounted on the holder 110 adapted to engage in the grooves whereby to secure the pins against movement.

2. In a device of the class described the combination of a holder having a slot extending longitudinally thereof, and a pair of bores, the bores being disposed beyond the opposite ends of the slot, pins adapted to be moved thru the bores and having seats formed in them, a blade mounted on the pins adapted to extend over the slot whereby the blade and holder may be retained in a co-

operating relationship to slice articles, and 10 clips mounted on the holder adapted to engage the seats in the pins and to fix the pins and blade on the holder.

In testimony whereof, I have hereunto subscribed my name this 15th day of April, 15 1922.

HENRY GEHRING.
